[57] CLAIM

The ornamental design of a mounting for supporting a portable light in operating position, as shown and described.

DESCRIPTION

FIG. 1 is a front elevational view of a mounting for supporting a portable light in operating position showing my new design;

FIG. 2 is a left side elevational view, with the opposite side being a mirror image thereof;

FIG. 3 is a rear elevational view thereof;

FIG. 4 is a top plan view thereof; and

FIG. 5 is a bottom plan view thereof.

FIG. 1

FIG. 2

FIG. 3

FIG. 4

FIG. 5
